UNITED STATES PATENT OFFICE.

HENRY J. FOSTER, OF NEW YORK, N. Y., AND JOHN M. HOWLEY, OF BAYONNE, NEW JERSEY.

ELEVATOR-SIGNALING DEVICE.

Application filed April 29, 1921. Serial No. 465,382.

To all whom it may concern:

Be it known that we, HENRY J. FOSTER and JOHN M. HOWLEY, residing at New York and Bayonne, in the counties of Bronx 5 and Hudson and States of New York and New Jersey, have invented certain Improvements in Elevator-Signaling Devices, of which the following is a specification.

This invention relates to an improved signaling arrangement for elevators.

A former arrangement for signaling in elevator systems, which comprise a plurality of elevators, has been to provide each elevator with a separate signal. With such arrangements, when a passenger would press a button to signal an elevator to stop at a floor, the indication of which of the elevators to be the next to stop at that floor would be given by an individual signal at each elevator door. This made it necessary for the passenger after pressing the signal button to watch all of the separate signals until one of them functioned. Such an operation would at times be difficult and cause much annoyance, particularly if the number of elevators was great or if the elevators were situated in a corner of the building. With the arrangements of this invention the individual signals may be eliminated and a central signaling panel is provided, whereby, when the button is pressed, an indication will be given of the next car to stop at that floor. With such an arrangement the passenger will only have to watch one place for the signal indication. Furthermore a considerable saving in equipment may be effected and the wiring system may be greatly simplified. Other features and advantages of the invention will appear more fully from the detailed description herein-after given.

The invention may be more fully understood from the following description together with the accompanying drawing, in the Figures 1, 2, and 3 of which are illustrated the arrangements thereof. Similar reference characters have been utilized to denote like parts in all of the figures of the drawing.

In Fig. 2 is shown one of the former types of elevator signaling arrangements. There is illustrated the doors 11, 12, 13 and 14 of elevators which may be referred to as the #1, #2, #3, and #4 elevators respectively. Between each of the elevators

might be the push buttons, such as 19, for signaling the cars. Above each elevator door might be an individual signal panel, such as the panels 15, 16, 17 and 18. To signal a car to go up or down the prospective passenger would push the "up" or "down" button of any of the push buttons 19. The passenger would then have to watch all of the signal panels, such as 15, 16, 17, and 18, until the flashing of the signal in one of these would indicate which of the four elevators was the next one to stop at that floor. As has been pointed out this might cause considerable difficulty and inconvenience especially if there should be a great number of elevators or if the elevators should be arranged in angular fashion as in the corner of a building.

In Fig. 3 is shown the improved signaling arrangement of this invention. Instead of the separate signal panels individual to each car there is provided, preferably at a centrally located position, a single signal panel 25 for all of the cars. Above each of the car doors there might be a stationary number, such as the numbers 1, 2, 3 and 4, in the panels 21, 22, 23, and 24. In the signal panel 25 there is provided a "down" and an "up" sign and two sets of numbered signals to correspond to the numbers above the cars. Upon pressing one of the push buttons 19 to go down the passenger will immediately see the "down" sign flash on panel 25 and later one of the numbered signals, such as 2, will flash to indicate that the #2 car is the next one to stop at the floor on the way down. Should the passenger press one of buttons 19 to go up, the "up" sign will flash on panel 25 and later one of the numbered signals, such as 1, will flash to indicate that the #1 car is the next to stop at that floor on the way up. With this arrangement the prospective passenger will only have to watch one signal panel, such as panel 25, after signaling the car and upon its operation may move over toward the proper car with much less confusion and trouble than in previous arrangements.

In Fig. 1 is shown a circuit diagram of the arrangement of the invention. 32 represents an elevator car which may be termed the #2 car, and may be assumed to be making its downward trip. 31 is an elevator car which may be termed the #1 car which is making its upward trip. The push buttons 110

19 are shown for signaling a car. The signaling panel provided at each floor is shown as 25. The arrangements for controlling the signals might be placed at any suitable 5 place in the building, such as on the top floor above the elevators. Accordingly, they have been shown as separated from the elevators and signaling panel by the dotted line XX. In this arrangement there would 10 be provided for every floor at which the cars would stop, a set of four relays such as relays 33, 34, 35 and 36. These relays would be individual to each floor, but would be common to all of the cars. For each car 15 would be provided a set of "up" segments and a set of "down" segments. The "up" segments for the car 32 are illustrated, while the "down" segments for car 31 are illustrated. The "up" segments for car 32 are 20 the segments 39, 40, 41, 42, 43, 44, 45, 46, 47, 48 and 49, while the "down" segments for car 31 are shown as 39' to 49' inclusive. The segments 40, 43 and 47 are for the floor at which the car is stopping in 25 the diagram, while the segments 39, 42 and 46 are for the next floor, and segments 41, 44 and 48 would be for another floor. The segments 39' to 49' are arranged in a similar manner. Cooperating with each set of 30 segments are the brushes 50 and 50'. The brush 50 is caused to move across the segments by the downward movement of the car 32 by mean of any suitable arrangement, such as the cables and pulleys herein illustrated schematically by the dotted line 52 35 and the pulley 51. The brush 50' will be caused to move across the segments 39' to 49' by a suitable arrangement, such as the cables and pulleys, upon the upward movement of the car 31. The cable is shown 40 schematically by the dotted line 54 and the pulleys as 53, 55 and 56. To provide current for operating the relays and signals, the generators 57 and 58 are provided. 45 The operation of signaling one of the cars going down, such as the car 32, is as follows: The prospective passenger would press one of the down buttons of the push buttons 19. This would close the following circuit—from the down push button 19, conductors 59 and 60, generator 58, conductor 61, winding of relay 35, conductors 62 and 63, to the other terminal of the down push button. This will operate the relay 35. The 50 relay 35 will attract its armature and thereby release the armature of the relay 33, which, due to its spring connection, will close its contact. This will close the following circuit: From the armature of relay 33, conductor 64, generator 57, conductor 65, 55 conductor 66 and the contact of relay 35, to the armature thereof. This will cause the "down" signal in panel 25 to flash, thereby informing the prospective passenger that

his signal has operated. Upon the operation of relay 36 the following circuit will also be closed: From the armature of relay 36, conductor 64, generator 57, conductor 67, conductor 68, conductor 69, through the #2 70 lantern in panel 25, conductor 70, conductor 80, to segment 40. When the car 32 is approaching the floor so that brush 50 will rest upon the segment 40, the above traced circuit will be completed from segment 40 75 through the brush 50, segment 43, conductor 81, contact and armature of relay 36. This will operate the #2 lantern in the panel 25 and inform the prospective passenger that the #2 car will be the next one 80 to stop at that floor on its downward trip. A circuit will also be completed for the lamp 37 in the car 32 to signal the operator thereof to stop at the floor, as follows: From the armature of relay 36, conductor 64, generator 57, conductor 67, conductor 68, through the filament of lamp 37 in the car, conductor 82 to the segment 45. When the brush 50 rests upon the segment 43, the above traced circuit will be completed as 85 follows: From segment 45 through the brush 50, segment 43, conductor 81, contact and armature of relay 36. After the car has stopped at the floor and continued on its down passage, the lights in the signaling panel 25 will be put out and the apparatus restored to normal in the following manner: When the car leaves a floor the brush 50 will momentarily rest on the segment 47. This will close the following circuit: From the segment 47 through the brush 50, segment 49, conductor 83, conductor 84, generator 58, conductor 61, winding of relay 36, conductor 85, conductor 86, to the segment 47. The closing of this 90 circuit will operate on relay 36, which will pull up its armature and open the previously traced operating circuits for the signals at its contact point. The armature of relay 36 will be held in its open position 95 by the armature of the relay 35. The operation for signaling one of the up-coming cars, such as the car 31, would be as follows: The prospective passenger would press one of the "up" buttons of the 100 push buttons 19 and thereby close the following circuit; from contact of button 19, conductor 59, conductor 60, generator 58, conductor 61, winding of relay 33, conductor 90, conductor 91, to the other contact of the 105 "up" push button. This will operate the relay 33, which will attract its armature and thereby release the armature of relay 34, allowing said armature to close the following circuit: From the armature of relay 34, conductor 64, generator 57, conductor 65, through the "up" signal in panel 25, conductor 92, conductor 93, contact and armature of relay 34. This will cause the "up" signal 110 in panel 25 to flash and inform the pro- 115

spective passenger that the car will be signaled. The operation of relay 33 will also close the following circuit: From the armature of relay 34, conductor 64, generator 57, conductors 94, 95 and 96, through the #1 "up" signal of panel 25, conductor 97, conductor 98 to the segment 40'. When the car approaches a floor, the brush 50' will be caused to move into contact with the segment 40'. The above traced circuit will then be completed as follows: From segment 40', brush 50', segment 43', conductor 99, conductor 93, contact and armature of relay 34. This will cause to flash the #1 "up" signal in panel 25 and thereby inform the prospective passenger that the #1 car will be the next car to stop at that floor.

A signaling circuit for the light in the car will be completed as follows: From the armature of relay 34, conductor 64, generator 57, conductors 94 and 95, filament of lamp 38, conductor 100 to the segment 45'. When the brush 50 is moved into contact with the segment 43', this circuit will be completed: From segment 45', brush 50', segment 43', conductor 99, conductor 93, contact and armature of relay 34. After the car has stopped at the floor for the passenger and moves on to the next floor, the brush 50' will move into contact with the setback segment 47'. This will close the following circuit: From the setback segment 47', conductor 101, winding of relay 34, conductor 61, generator 58, conductor 60, conductor 102, conductor 103 to the segment 49', and from the segment 49' through the brush 50' to the segment 47'. This will operate the relay 34 which will pull up its armature and open the previously traced signaling and relay circuits. Relay 33 will thus be de-energized, and by releasing its armature will cause the armature of relay 34 to be held in its open position.

While the wire connections to the segments have only been shown for one floor, it is pointed out that the other segments would be wired in a similar manner to other relay arrangements and to signaling arrangements at other floors. For example, segments 39, 42 and 46 would be wired to the signaling arrangements for the floor below those illustrated, while segments 41, 44 and 48 would be provided for the signaling arrangements for the floor above.

A lead is shown from the #2 "up" light, which would lead to the other lantern segments of the #2 car going up. A lead is shown from the #1 "down" signal, which would lead to the other lantern segments of the #1 car going down. The lantern segments would be the segments such as 39, 40, and 41, and 39', 40' and 41'. A lead is shown from conductor 85, which would lead to setback segments corresponding to 47 of

all the other cars going down. A lead is shown from conductor 101, which would lead to setback segments corresponding to 47' of other cars going up. The conductors 90 and 105 would also be connected to other "up" push buttons and to other "down" push buttons respectively, while the conductor 60 would lead to the other push button connections. The conductor 94, in turn, would be connected to lamps of other cars. As the description of the operation of the arrangements for other cars would be substantially the same as that already described, no further description thereof will be given.

While the arrangements have been disclosed in certain specific arrangements which are deemed desirable, it is understood that they are capable of embodiment in many and widely varied forms without departing from the spirit of the invention as defined in the appended claims.

What is claimed is:

1. In an elevator signal system including a plurality of numbered elevators, a visual signal panel for each floor, said panel being common to all of said cars and having signals individual to each car and other signals indicating the direction in which the passenger desires to go, an "up" push button and a "down" push button at each floor, means responding to the operation of one of said push buttons to prepare a circuit for each of the car signals of the panel at said floor and to simultaneously close an operating circuit for the direction signal of said panel corresponding to the push button operated, thereby indicating that the signal system is working and that the car signal circuits are prepared, and means operated by an individual car moving in the direction indicated by the panel as it approaches the floor to complete the circuit of the corresponding car signal of the panel at that floor.

2. In an elevator signal system including a plurality of numbered elevator cars, a visual signal panel at each landing, said panel including an "up" signal and a "down" signal common to the cars and an individual signal for each car for each direction, "up" and "down" push buttons at each landing common to all of the cars, means controlled by a push button at the landing whereby the corresponding direction signal for that landing is operated immediately, and means jointly controlled by said last mentioned means and a car whereby a signal individual to said car is operated when the car approaches the landing.

3. In an elevator signal system including a plurality of elevators, a signal panel located at a landing, said signal panel including a direction signal and a set of individual signals corresponding to said elevators, a set of push buttons, means controlled solely by

said push buttons for operating said direction signal, and means controlled jointly by each of said elevators and said last mentioned means for operating the individual signal corresponding to said elevator, said direction signal being operated immediately upon the actuation of said push buttons and said individual signals being operated by

said cars when said cars arrive at a certain distance from said landing.

In testimony whereof, we have signed our names to this specification this 23th day of April, 1921.

HENRY J. FOSTER.
JOHN M. HOWLEY.
